UNITED STATES PATENT OFFICE.

FRANK E. DAVIS, OF LA CROSSE, WISCONSIN

PLOW.

964,762.

Specification of Letters Patent. Patented July 19, 1910.

Application filed June 10, 1907. Serial No. 378,129.

To all whom it may concern:

Be it known that I, FRANK E. DAVIS, a resident of La Crosse, in the county of La Crosse and State of Wisconsin, have invented certain new and useful Improvements in Plows, of which the following is a full, clear, and exact description.

The invention relates to plows, and more particularly to that type in which carrying-10 wheels, a supporting-frame and mechanism for raising and lowering the plow or plows are employed, such type being generally known as riding plows.

In plow-operating mechanisms as heretofore constructed, it is customary in many instances, to employ a direct connection between the operating-lever and the plow-operating crank or bail and in other instances a link is included in the connection between 20 the operating-lever and the plow. When a lever mounted to swing eccentrically with respect to the plow-operating crank or arm is employed in a foot-operable shifting mechanism, the lever must be of considerable 25 length and given an extended sweep so a short operating crank or bail can be employed in order to render the mechanism conveniently operable by foot. An extended sweep of such a long foot-lever is objectionable because the operation is rendered inconvenient and slow. When a link-connection is associated with an operating-arm of the lever and the plow-operating bail or crank and said lever are of differential length and 35 they are brought into dead-center relation or substantially so, to lock the plow in one of its alternative positions, the sweep of the foot-lever cannot always be disposed so that it is conveniently operable by one foot of the 40 operator. As a result of the same construction when an extended sweep of the foot-lever is employed to cause the operating-arm of the link-connection to travel over a sufficient arc to operate the plow from one 45 of its positions to the other, the operation of the foot-lever during a portion of its sweep is effected with difficulty.

The present invention designs to provide a construction of plow-shifting mechanism 50 in which the sweep of the operating lever is disposed for convenient operation by the foot of the operator and in which a differential or compound leverage is attained by which the greatest power is applied during 55 that portion of the lifting or lowering move-

ment of the plow in which it is necessary, i. e., when the soil resists its movement.

The invention further designs to provide an improved foot-operable lifting-mechanism for the plow and also an improved foot-operated or controlled lowering mechanism.

The invention consists in the several novel features hereinafter set forth and more particularly defined by claim at the conclusion hereof.

In the drawings: Figure 1 is an elevation from the land-side, the land-wheel being shown in dotted lines, and the plow in raised position. Fig. 1^a is a detail of the plow lifting-mechanism in position assumed when the plow is in lowered or working position. Fig. 1^b is a detail end view of the latch for holding the plow in raised position and its associated parts. Fig. 2 is a plan. Fig. 3 is a longitudinal section showing the improved plow-lowering mechanism. Fig. 3^a is a detail view showing the lowering mechanism in position assumed when the plow is in lowered position.

The invention is illustrated as applied to 80 a gang plow, although it will be understood that it may be applied to other types of plows.

10 denotes a plow-supporting-frame sustained by the usual front furrow-wheel, 11 85 and the rear furrow or caster wheel 12 in any suitable or usual manner and a land-wheel 13. These wheels are usually adjustably connected to the frame so the frame may be adjusted with respect to the ground 90 as well understood in the art. At the front of the frame an arch 14 transversely connects the sides of the supporting-frame 10. Furrow-wheels 11 and 12 have, as usual, a swiveled connection to the main frame, being respectively mounted on standards 15 and 16 which are swiveled in suitable brackets secured to the supporting-frame. One or more plows 18 are each secured to a beam 19 and supported by and connected to the main-frame at the front by a bail 20 which serves as a crank and is pivotally mounted in a bracket 61 at each side of the frame. The eccentric portion of the bail is pivoted to each plow-beam, being held in suitable brackets 20^b and serves to operatively connect the frame and the plow for raising or lowering movement. The rear of the plow is controlled by a guide-bracket 21 having a cam slot 22 therein which causes 110

the rear end of the plow to rise and fall in response to the operation of bail 20 and to control the horizontal position of the plow as bail 20 is moved forwardly and downwardly or upwardly and backwardly. A stud or roller-abutment 23 suitably connected to the main frame extends into or through slot 22, the latter being provided with an offset or seat 22^a at its front and lower end and an offset or seat 22^b at its upper end, the guide in its entirety being formed so that as a result of movement of bail 20 the plow or plows will enter the ground point first and then assume a correct and true position for plowing and so the plow-point will rise point first to facilitate the withdrawal of the plow from the ground by the draft of the team. Guide 21 is secured to bars 24 which are rigidly secured to one of the plow-beams 19. The fronts of the plow-beams are connected by a clevis-bar 25 to which the team is connected. A lifting or counter-balancing spring 26 is applied to assist in the lifting-operation and to resist descent of the plow; being connected at one end to a lug or bracket 27 secured to frame 10 and at its other end to a lug 28 secured to one of the plow-beams. A foot-rest 29 for one of the feet of the operator is secured to one of the beams 19 and a rest 30 is secured to the frame 10 for the other foot of the operator. The land-wheel is adjustably connected to the main frame, being journaled on a stud or stub-axle 31 which is secured to the distal end of a bracket 32 which is pivotally mounted on the projecting end 20^a of the bail 20. A lever 33 is secured to bracket 32 and is provided with the usual lever-lock 34, which is adapted to engage a rack 35 which is non-rotatably and rigidly secured to the main frame by a laterally extending lug or bracket 36. A seat 37 for the operator is suitably sustained by the frame.

45. The improved lowering-mechanism comprises a foot-lever 38 which is pivotally mounted on the eccentric portion of bail 20, being secured against lateral displacement thereon by a hook-jug 39 which is adapted to travel in a grooved collar 40 which is clamped to the bail. Foot-lever 38 has a treadle or foot-piece 41 at its rear end and extends forwardly of its pivot to form an arm 42 in which an angular slot 43 is formed. A bracket 44 is secured to frame-arch 14 by a bolt 45 and is extended to provide a pivot 46 at the front end of a strut or link 47 which is connected at its rear end by a bolt 48 to the foot-lever 38, the bolt extending through angular slot 43 and having a friction roller thereon which is adapted to travel in the slot. Arm 42 of foot-lever 38 is provided with a stud or abutment 49, which is adapted to rest in a seat or notch 50 in link 47 to interlock the foot-lever and

the link by resisting any forward and downward movement of the plow-operating bail 20 when foot-lever 38 is in normal position, (Fig. 3). In the position illustrated in Fig. 3, the plow being then raised, stud 49 and 70 the seat 50 form a dead-center locking-device between the lever arm 42 which is pivoted on the bail and link 47 which is pivoted as at 46 to the main frame. A notch 49' is also provided for similarly locking 75 the plow in a somewhat lower position, this being for the convenience of a rider with short legs who finds it inconvenient to lift the plow to the extreme upper position shown in Fig. 3. A spring 51 is applied to 80 a rod 52 which is pivotally connected as at 53 to arm 42 of the foot-lever to yieldingly hold the foot-lever so that the foot-lever will be yieldingly held in position to prevent withdrawal of the stud 49 from its 85 seat 50 when the lowering-connection is locked to hold the plow in raised position. Rod 52 is guided in a slot 54 formed in bracket 44 and, being yieldingly held, permits the foot-lever to be swung by the operator to release the lowering-connection. For convenience in construction, plural links 47 are provided which are cross connected by bolt 48 and lever-arm 42 is disposed between said links. 90

95. The operation of the plow lowering-mechanism will be as follows: Assuming the plow to be in raised position (Fig. 3) the operator will depress lever 38 and during the initial movement thereof said lever will 100 swing about crank 20 as a fulcrum and withdraw stud 49 from notch 50 of link-strut 47. Rod 52, which is yieldingly held by spring 51, extends loosely through slot 54 in bracket 44, yielding sufficiently to permit the lever 38 to be swung into position to disengage the stud 49 from notch 50. The lowering-connection will then be unlocked so that lever 38 will be free to be further depressed. During further depression of the treadle 41 on lever 38 the front end of said lever will be pressed against upward movement by rod 52 and the crank 20 and plow will be lowered until they reach the position shown in Fig. 3^a. During the initial lowering movement of crank 20 stud 48 on lever-arm 42 will remain in the horizontal portion of the angular slot 43 and resist backward movement of lever-arm 42 so that the foot-lever 38 will be 110 operated about said stud as a movable fulcrum and then as the lowering movement of the crank 20 continues the stud will slide 115 backwardly in the slot 43 and pass into the end 43^a of said slot. The angular slot thus 120 guides the strut-link so that stud 49 will not pass into either of the notches 49' or 50 during the lowering operation of the plow. During this lowering movement the stud and slot connection between the link 47 and 125 130

lever arm 42, result in a gradual increase of the leverage applied by the foot-lever to the crank so that during the latter portion of the lowering-movement, when the plow 5 is entering the soil, greater leverage is attained than during the initial lowering movement when there is little resistance to the lowering of the plow. Furthermore, as a result of this construction, the sweep of lever 38 is arranged for substantially vertical movement and convenient operation by the operator and the power is differentially applied. The disposition of the link-strut and the lever-arm is such that they automatically 10 pass into locking-position when crank 20 is shifted to raise the plow by mechanism hereinafter set forth. Manifestly the sliding connection between the lever and link provided by angular slot 42 causes the force of the lever to be compounded or differentially applied and the arrangement of the parts for self-locking and release thereof by the foot-lever facilitates the lowering thereof so that the plow 15 can be controlled by the operator with ease.

Foot-operable plow lifting-mechanism is provided and comprises an arm 60 keyed or rigidly secured to the bail fulcrum or shaft 20. A foot-lever 62 is pivoted as at 63 to the frame and said pivot is eccentrically disposed with respect to the bail fulcrum so that during shift of said lever it will swing eccentrically with respect to arm 60 and cause the lever to be differentially applied to the arm to apply greatest leverage during the initial upward shift of the plow, *i. e.*, when the plow is being lifted out of the soil. To effect this differential application of power a sliding-connection is provided in the connection which causes the force of the lever to be differentially applied during a lifting operation. In the embodiment of the invention shown, lever 62 has a sliding connection with the outer end of arm 60 which is bifurcated and provided with a friction roller 63' which is engaged by the lever. This sliding connection causes variation of the point of application of power between the lever and the arm to effect the differential operation aforesaid. An automatic locking device is provided for securing the plow in lowered position, this being operable by the foot-lever so that when the operator depresses the foot-lever 62 the initial movement thereof will release the locking-device. This locking device comprises a dog or latch 64 which is pivotally connected to bolt 65 at the outer end of arm 60, is 25 yieldingly pressed into operative position by a rod 66 pivoted to a lug 67 on the latch and a spring 68 applied to said rod. Dog 64 is bifurcated and the lever 62 passes therethrough and is provided with a lug 69 adapted to engage arm 60 to limit its movement in one direction by spring 68. The

dog is provided with an offset hook 70 adapted to engage with a lug 71 integrally formed with bracket 61, when the lifting-mechanism is in position, to hold the plow in lowered position. A stud or abutment 72 70 on foot-lever 62 is adapted to engage the edge of dog 64 to initially release dog-hook 70 from lug 71 and release the lifting mechanism.

When the plow is in lowered position the foot-operable lifting-mechanism is in the position illustrated in Fig. 1a. The lifting operation will be as follows: When the operator depresses lever 62 about its fulcrum 63, stud 72 on said lever will engage inclined lug 69 and swing the latch 64 rearwardly about its pivot 65 against the force of spring 68 and free the latch from lug 71 to release the plow. Further movement of foot-lever 62 will cause it to engage roller 63 at the end 80 of arm 60 and initially at a point close to lever-fulcrum 63. As a result of the swinging movement of said arm and lever about their relative eccentric pivots respectively and the sliding connection for the foot-lever, 85 the initial movement of the lever will be applied at the point of greatest leverage, and the distance between the lever-fulcrum and the point of applied power of the lever is gradually increased so the leverage will 90 become less. Resultantly greater leverage is attained during the initial upward movement when the plow must overcome the resistance of the soil than during the latter part of the upward movement when the 95 plow is out of the soil and is easily operable by the foot-lever, when the least leverage is employed. In the lifting mechanism the several parts thereof are sustained so that all 100 parts are freely shiftable in response to the lever and the mechanism in its entirety is operable with ease. The lifting-mechanism is restored to operative position by the lowering mechanism and vice versa.

The invention is not to be understood as 110 restricted to the precise details shown and described, since these can be varied without departing from the spirit and scope of the invention.

Having thus described the invention, what 115 I claim as new and desire to secure by Letters Patent, is:

1. In a riding-plow, the combination of carrying-wheels, a frame, a plow, plow-shifting mechanism comprising a pivoted 120 arm, a lever mounted to swing eccentrically with respect to said arm, and a sliding connection for varying the operative length of one of said elements so that the force of the lever will be differentially applied to shift 125 the plow, and an automatically operated locking-device for holding the plow in one of its positions.

2. In a riding-plow, the combination of carrying-wheels, a frame, a plow, plow lift. 130

- ing mechanism comprising a pivoted arm, a lever mounted to swing eccentrically with respect to said arm and a sliding connection for varying the operative length of one of said elements so that the force of the lever will be differentially applied to lift the plow, an automatically operated locking-device for the plow, and a plow-lowering mechanism.
10. 3. In a riding-plow, the combination of carrying-wheels, a frame, a plow, plow-lifting-mechanism comprising a pivoted arm, a foot-lever mounted to swing eccentrically with respect to said arm and a sliding-connection for varying the operative length of one of said elements so that the force of the lever will be differentially applied in lifting the plow, a foot-operable plow-lowering-mechanism, and an automatically operating locking-device for the lifting-mechanism.
4. In a riding-plow, the combination of carrying-wheels, a frame, a plow, plow-shifting-mechanism comprising an arm operatively connected to the plow, a lever for operating said arm, means for varying the distance between the point of application of the force of the lever and the lever pivot to differentially apply the force of said lever to said arm, and an automatically operating locking-device for said mechanism.
5. In a riding-plow, the combination of carrying-wheels, a frame, a plow, plow-lifting-mechanism comprising an arm operatively connected to the plow, a lever for operating said arm and means for varying the distance between the point of application of the force of the lever and the lever pivot, to differentially apply the force of said lever to lift the plow, and an automatically operating locking-device for said mechanism.
6. In a riding-plow, the combination of carrying-wheels, a frame, a plow, plow-shifting-mechanism comprising an arm operatively connected to the plow, a foot-lever for operating said arm, means for varying the distance between the point of application of the force of the lever and the lever pivot to differentially apply the force of said lever to said arm, an automatically operating locking-device for said mechanism, and a foot-operable lowering mechanism.
7. In a riding-plow, the combination of carrying-wheels, a frame, a plow, plow-shifting-mechanism comprising a pivoted arm connected to the plow, a lever mounted to swing eccentrically with respect to said arm, and a sliding connection between said lever and said arm whereby the force of the lever will be differentially applied to the arm and an automatically operated locking-device operable by said lever.
8. In a riding-plow, the combination of carrying-wheels, a frame, a plow, plow-lifting-mechanism comprising a pivoted arm connected to the plow, a lever mounted to swing eccentrically with respect to said arm, and a sliding connection between said lever and said arm whereby the force of the lever will be differentially applied to the arm, 70 and an automatically operated locking-device operable by said lever.
9. In a riding-plow, the combination of carrying-wheels, a frame, a plow, plow-lifting-mechanism comprising an arm connected to the plow, a foot-lever mounted to swing eccentrically with respect to said arm and a sliding-connection between the arm and lever whereby the lever will be differentially applied to the arm, a plow-lowering mechanism, said lifting-mechanism being connected so it will be restored to operative position by the lowering mechanism and a locking-device operable by said foot-lever.
10. In a riding-plow, the combination of carrying-wheels, a frame, a plow, plow-lifting-mechanism comprising an arm operatively connected to the plow, a lever mounted to swing eccentrically with respect to the arm, and a sliding connection between the lever and the arm for differentially applying the force of the lever to said arm, a latch for locking the arm to secure the plow in lowered position, and means operated by said lever for releasing said latch.
11. In a riding-plow, the combination of carrying-wheels, a frame, a plow, front and rear sustaining-connections between the frame and the plow, plow-shifting-mechanism comprising a pivoted arm connected to one of said connections, a lever mounted to swing eccentrically with respect to said arm, and a sliding-connection for varying the operative length of one of said elements so that the force of the lever will be differentially applied to shift the plow.
12. In a riding-plow, the combination of carrying-wheels, a frame, a plow, front and rear sustaining-connections between the frame and the plow and plow-lifting-mechanism, and comprising an arm connected to one of said connections, a lever mounted to swing eccentrically with respect to said arm, a sliding-connection whereby the operative length of one of the said elements will be varied so that the force of the lever will be differentially applied to lift the plow, and a foot-operable lowering mechanism.
13. In a riding-plow, the combination of carrying-wheels, a frame, a plow, front and rear sustaining-connections between the frame and the plow and plow-shifting-mechanism comprising an arm pivoted in the frame and operatively connected to one of said connections, a lever mounted to swing eccentrically with respect to said arm, and a sliding connection between the arm and the lever whereby the power of the lever will be differentially applied as the arm is shifted thereby.

14. In a riding-plow, the combination of carrying-wheels, a frame a plow, a plow supporting crank at the front, a rear sustaining connection between the frame and the plow, and plow shifting-mechanism comprising an arm rigidly secured to said crank, a lever pivoted to said frame eccentrically with respect to said shaft, and a sliding connection between the arm and the lever, and a locking-device releasable by said lever.
15. In a riding-plow, the combination of carrying-wheels, a frame, a plow, a plow supporting crank at the front, a rear sustaining connection between the frame and the plow and plow shifting-mechanism comprising an arm rigidly secured to said crank, a foot-lever pivoted to said frame eccentrically with respect to said crank, and a sliding connection between the arm and the lever, and a locking-device releasable by said lever.
16. In a riding-plow, the combination of a frame, carrying-wheels therefor, a plow and plow shifting-mechanism for shifting the plow comprising a lever and a link, one of which is connected to the frame and the other of which is connected to the plow, and a sliding connection for one of said parts which causes the force of the lever to be differentially applied so that the leverage will be varied during the operation of the lever.
17. In a riding-plow, the combination of a frame, carrying-wheels therefor, a plow and plow-shifting mechanism comprising a link and a lever one of which is connected to the frame and the other of which is connected to the plow, and a sliding-connection between the link and the lever whereby the power of the lever will be differentially applied to the plow.
18. In a riding-plow, the combination of a frame, carrying-wheels therefor, a plow, plow-shifting mechanism comprising a lever and a link, one of which is connected to the frame and the other of which is connected to the plow, and a sliding-connection for one of said parts which causes the force of the lever to be differentially applied, and an automatically operating locking device for said mechanism.
19. In a riding-plow, the combination of a frame carrying-wheels therefor, a plow, plow-shifting mechanism comprising a link and a lever one of which is connected to the frame and the other of which is connected to the plow, a sliding-connection between the link and the lever whereby the power of the lever will be differentially applied to shift the plow, and a locking-device operated by said lever.
20. In a riding-plow, the combination of a frame, carrying-wheels therefor, a plow and mechanism for shifting the plow comprising a link pivotally connected to the frame, a lever pivotally connected to the plow, a sliding-connection between the link and said lever whereby the force of said lever will be differentially applied.
21. In a riding-plow, the combination of a frame, carrying-wheels therefor, a plow and mechanism for shifting the plow comprising a link pivotally connected to the frame, a lever pivotally connected to the plow, a sliding-connection between the link and said lever whereby the force of said lever will be differentially applied, and a locking-device operated by said lever.
22. In a riding-plow, the combination of a frame, carrying-wheels therefor, a plow and operating-mechanism for shifting the plow comprising a bail, a link, and a lever, one of which is pivoted to the frame and the other of which is pivotally and eccentrically connected to the bail, and a sliding connection which causes the force of the lever to be differentially applied to said crank or bail.
23. In a riding-plow, the combination of a frame, carrying-wheels therefor, a plow and mechanism for shifting the plow comprising a bail connecting the plow and the frame, a link pivoted to the frame, and a lever pivotally connected to the bail and a sliding-connection between said link and said lever.
24. In a riding-plow, the combination of a frame, carrying-wheels therefor, a plow, mechanism for shifting the plow comprising a bail between the frame and the plow, a link, and a foot-lever, one of which is connected to the frame and the other of which is connected to the plow, a sliding-connection for causing the lever to be differentially applied and a locking-device for holding the lever and link in dead-center relation to cause the same to lock the plow in one of its positions.
25. In a riding-plow, the combination of a frame, carrying-wheels therefor, a plow and mechanism for shifting the plow comprising a crank-connection between the frame and the plow, a link pivoted to the frame, a foot-lever pivotally connected to said crank, and a sliding and pivotal connection between the lever and the link.
26. In a riding-plow, the combination of a frame, carrying-wheels therefor, a plow, mechanism for shifting the plow comprising a crank between the frame and the plow, a link pivoted to the frame, a foot-lever pivotally connected to said crank, a sliding and pivotal connection between the lever and the link, and an automatically operating locking device for said connection.
27. In a riding-plow, the combination of carrying-wheels, a frame, a plow, a foot-operable plow lowering mechanism, a foot-operable plow lifting-mechanism, a locking device for the lowering-mechanism actuated

by the lifting-mechanism, and a locking-device for the lifting-mechanism actuated by the lowering mechanism.

28. In a riding-plow, the combination of 5 carrying-wheels, a frame, a plow, plow lifting-mechanism, a foot-lever for the lifting-mechanism, a plow lowering-mechanism, a foot-lever for the lowering-mechanism, a locking-device for the lowering-mechanism, 10 releasable by the foot-lever of the lowering-mechanism and actuated by the lifting-mechanism, and a locking-device releasable by the foot-lever of the lifting-mechanism and actuated by the lowering mechanism.
29. In a riding-plow, the combination of 15 carrying-wheels, a frame, a plow, plow shifting-mechanism comprising a pivoted arm, a lever mounted to swing eccentrically with respect to said arm, a sliding connection for 20 varying the operative length of one of said elements so that the force of the lever will be differentially applied to shift the plow and automatically operated locking-devices for respectively holding the plow in raised 25 and lowered position.

30. In a riding-plow, the combination of carrying-wheels, a frame, a plow, plow shifting-mechanism comprising a pivoted arm, a foot-lever mounted to swing eccentrically 30 with respect to said arm, a sliding connection for varying the operative length of one of said elements so that the force of the lever will be differentially applied to shift the plow, and automatically operated locking-devices for respectively holding the plow in raised 35 and lowered positions.

31. In a riding plow, the combination of carrying-wheels, a frame, a plow, plow shifting-mechanism comprising an arm 40 connected to the plow, a lever for operating said arm, means for varying the distance between the point of application of the force of the lever and the lever pivot to differentially apply the force of said lever 45 to said arm and automatically operating locking-devices for respectively holding the plow in raised and lowered positions.

32. In a riding-plow, the combination of carrying-wheels, a frame, a plow, plow lifting-mechanism comprising an arm connected 50 to the plow, a foot-lever mounted to swing eccentrically with respect to said arm, a sliding connection between the arm and the lever whereby the lever will be differentially applied to the arm, a plow lowering mechanism and automatically operated locking-devices respectively operated by said mechanism for holding the plow in raised 55 and lowered positions.

33. In a riding-plow, the combination of 60 a frame, carrying-wheels, a plow, plow shifting-mechanism comprising a link and a foot-lever one of which is connected to the frame and the other of which is connected to the plow, a sliding-connection between

the link and the lever whereby the force of the lever will be differentially applied to the plow, and locking-devices for respectively holding the plow in raised and lowered positions.

34. In a riding-plow, the combination of 70 carrying-wheels, a frame, a plow, plow lowering-mechanism comprising a lever and a link, one of which is connected to the frame and the other of which is connected to the 75 plow, a sliding connection for one of said parts which causes the force of the lever to be differentially applied, a foot-operable lifting-mechanism and locking-devices respectively actuated by said mechanisms to 80 hold the plow in raised and lowered positions.

35. In a riding-plow, the combination of 85 a frame, carrying-wheels, a plow, plow lowering-mechanism comprising a foot-lever, a link, and a sliding connection between the link and the lever, and plow lifting-mechanism comprising a foot-lever, an arm and a sliding connection, and automatically operated locking-devices for said mechanisms. 90

36. In a riding-plow, the combination of 95 a frame carrying-wheels, a plow, plow-lowering mechanism comprising a foot-lever, a link and a sliding connection between the link and the lever, and plow-lifting-mechanism comprising a foot-lever, an arm and a sliding-connection, and locking devices respectively operated by said mechanisms and releasable by said foot-lever.

37. In a riding-plow, the combination of 100 a frame, carrying-wheels, plow lifting-mechanism comprising a foot-lever, and a locking-device for holding the lever in raised position, said mechanism being actuated by said foot-lever and means whereby said 105 mechanism may be operated to hold the plow in different raised positions.

38. In a riding-plow, the combination of 110 a frame, carrying-wheels, plow lifting-mechanism comprising a foot-lever, a foot-lever 110 for lowering the plow and a locking device actuated by the foot-lever of the raising mechanism and means for holding the plow in different raised positions and releasable by the foot-lever for lowering the plow. 115

39. In a riding-plow, the combination of 120 a frame, carrying-wheels, plow-lifting-mechanism comprising a foot-lever, a foot-lever for lowering the plow, a locking-device actuated by the foot-lever of the lifting-mechanism and releasable by the foot-lever for lowering the plow, a locking-device for holding the plow in lowered position, and means for holding the plow in different 125 raised positions.

40. In a riding-plow, the combination of 130 a frame, carrying-wheels therefor, a plow, mechanism for shifting the plow comprising a link pivoted to the frame, and a crank, a lever pivotally connected to said crank, a

sliding and pivotal connection between the lever and the link, an automatically operating locking-device for said connection, and a spring for holding the connection in 5 one of its positions.

41. In a riding-plow, the combination of carrying-wheels, a frame, a plow, a crank-connection between the frame and the plow, lowering-mechanism for the plow comprising 10 a foot-lever and a link, one of which is pivoted to the frame and the other of which is pivotally connected to the plow, and a sliding-connection whereby the lever will be caused to apply its force differentially to the 15 plow, and means operated for locking the connection in different positions.

42. In a riding plow, the combination of carrying-wheels, a frame, a plow, a crank-connection between the frame and the plow, 20 lowering-mechanism for the plow comprising

ing a foot-lever and a link, one of which is pivoted to the frame and the other of which is pivotally connected to the plow, and a sliding-connection comprising an angular slot which causes the lever to be applied differentially in lowering the plow. 25

43. In a riding-plow, the combination of carrying-wheels, a frame, a plow, a crank-connection between the frame and the plow, lowering-mechanism for the plow comprising 30 a foot-lever and a link, one of which is pivoted to the frame and the other of which is pivotally connected to the plow, a sliding-connection which causes the force of the lever to be differentially applied, and a foot- 35 operable lifting-mechanism.
